FIBER CUTTING MACHINE

Jan V. Weinberger, Truro, Nova Scotia, Canada

Application July 13, 1944, Serial No. 544,799
In Canada April 17, 1943

9 Claims. (Cl. 164—61)

This invention relates to apparatus for cutting tangled masses of long fibers, particularly "nylon" and other artificial and natural fibers, into smaller masses of shorter fibers which can be easily separated from each other by a carding machine.

An important object of the invention is to provide cutting apparatus whereby each long fiber, regardless of its arrangement in the mass, will be cut transversely at a sufficient number of points along its length to divide it into shorter fibers which can readily be separated from similar short fibers entangled therewith.

The foregoing and other objects of the invention are attained by providing a fiber cutting machine consisting, essentially, of a series of rotary cutters, a fiber holder having two intersecting rows of grooves in one surface thereof, the grooves of each row being open at both ends and extending entirely across said surface at right angles to the grooves of the remaining row, and means for retaining a mass of tangled fibers against the grooved surface of the holder. The cutters and the fiber holder are first moved relatively to each other in fiber cutting relation so that the cutters traverse the grooves of one row and cut through the portions of the fibrous mass which extend across said grooves. The holder is then re-arranged so that when the cutters and holder are again moved relatively to each other in fiber cutting relation, the cutters will traverse the grooves of the remaining row and will cut through portions of the fibrous mass extending across said last mentioned grooves. In this way the large mass of fibers carried by the holder is divided, by intersecting cuts, into smaller separate masses of relatively short fibers which can readily be separated from each other.

Proceeding now to a more detailed description of this invention reference will be had to the accompanying drawings, in which—

Figure 1 is a perspective view of a fiber cutting apparatus embodying my invention.

Figure 2 is a perspective view of a portion of the apparatus and shows the manner in which the fiber holder is guided during the fiber cutting operation.

Figure 3 is a view similar to Figure 2 showing the manner in which the fiber holder is passed over the rotary cutters in fiber cutting relation thereto.

Figure 4 is a fragmentary longitudinal sectional view taken substantially along the line 4—4 of Fig. 3.

Figure 5 is a transverse sectional view taken substantially along the line 5—5 of Fig. 4.

Figure 6 is a plan view of the fiber holder as it appears when looking toward the grooved side.

Figure 7 is a plan view of the fiber holder as it appears when looking toward the side opposite the grooved side.

Figure 8 is an end view of the fiber holder.

Figure 9 is a plan view of a slat and end frame assembly which is employed for holding a mass of fibers against the grooved side of the fiber holder; and

Figure 10 is a perspective view illustrating the manner in which the slat and end frame assembly of Fig. 9 is assembled with the fiber holder to hold a mass of fibers in place against the grooved side of the holder.

Referring more particularly to the drawings, 5 designates a rotary shaft carrying a plurality of circular cutters 6 fixed to revolve therewith, said shaft being arranged between adjacent separated ends of two table sections 7 and 8 and being journaled in suitable shaft supports 9 attached to said table sections. One end of shaft 5 is driven by a pulley 10 and belt 11 from an electric motor 11a or other suitable prime mover, the direction of rotation of shaft 5 and cutters 6 being indicated by arrow 12.

A series of laterally spaced guide rails 13 are arranged on table section 7 so that each rail is substantially in line with one of the cutters 6. Similar rails 14 are arranged on table section 8 in accurate alignment with rails 13. The rails 13 and 14 are shown secured to the underlying table sections by bolts 15 but it will be understood that these rails may be secured in place in any other desired manner or may be formed as integral parts of the table sections. Generally, however, it is preferred that the rails of each series be formed as separate elements and adjustably secured to the underlying table sections so that the spacing of the rails of each series may be varied whenever such variation is necessary or desirable.

The table sections 7 and 8 and the rails mounted thereon may be made of wood or any other suitable material. Table sections 7 and 8 may be mounted on supporting legs 17, as shown in the drawings, or on any other suitable supporting structure.

A table 20, either portable or stationary, is arranged opposite and in spaced relation to that end of table section 8 which is remote from the cutter 6, the gap separating table 20 from table section 8 being bridged by two transfer rails 21 which are used for a purpose hereinafter described.

A table 23, similar to the table 20, is arranged

opposite and in spaced relation to that end of table section 7 which is remote from the cutters 6, the gap between table 23 and table section 7 being bridged by transfer rails 24 corresponding to the previously mentioned rails 21.

The various table elements and transfer rails mentioned in the preceding discussion are utilized to guide and support and to facilitate the necessary manipulation of the fiber holder 26 which, during each cutting operation, is moved over the cutters 6 from a starting position on table 20 to a finishing position on table 23. The preferred construction and assembly of the fiber holder 26 and the fiber retaining means associated therewith is clearly illustrated in Figs. 6 to 10 inclusive. As here shown, the fiber holder 26 comprises a rectangular member having one surface thereof interrupted by two rows of intersecting grooves, the component grooves of each row being parallel with each other and open at their opposite ends and extending entirely across said surface at right angles to the grooves of the companion row. These two sets of grooves, respectively indicated at 27 and 28, obviously serve to divide the grooved surface of the holder into a plurality of spaced, rectangular areas 29 which may be covered by emery paper, card clothing, or other fiber engaging means for reducing slippage between the holder and the means of fibers 31 (Fig. 10) which is held against and completely covers the entire area of the grooved surface of the holder. A row of slat engaging pins 32 project from the grooved surface of the holder along each of its marginal edges, said pins being adapted, as shown in Fig. 9, to extend through suitable holes 33 provided in the fiber retaining slats 34 which serve to hold the mass of fibers against the grooved surface of the holder.

A pair of grooved rollers 37 are rotatably mounted on stub shafts 38 projecting outwardly from those marginal edges of holder 26 which lie parallel with grooves 27. A second pair of grooved rollers 39 are similarly mounted on stub shaft 40 projecting outwardly from the remaining marginal edges of said holder. A plurality of casters 41 are swingably attached to the surface of holder 26 opposite that in which the grooves 27 and 28 are provided.

The slats 34 are assembled with the holder 26 so that they are separated from each other by intervening cutter receiving spaces which are aligned with those grooves of the holder which are to be traversed by the cutters 6 during the cutting operation. For example, in the case of the holder and slat assembly shown in Fig. 10 it is assumed that the grooves 27 of the holder will be traversed by the cutters 6 during the initial fiber cutting operation. In this case the slats 34 are fitted on the pins 32 so that they lie between and in parallel relation with the grooves 27, adjacent slats being separated from each other by an intervening cutter receiving space which is directly opposite one of the grooves 27. Since the slats 34 are necessarily formed as separate elements it is desirable that some means be provided whereby said slats may be conveniently handled as a unit. This may be accomplished by the provision of two slat holding end frames generally indicated at 43. Each end frame comprises a bar 44 provided with a row of short slat spacing projections 45 which are inserted in sockets 46 provided in the ends of the slats against which the bar is fitted. The bar 44 of each end frame terminates in parallel end portions 47 which extend a short distance along the outer sides of the outermost slats of the series and

are provided with holes 48 registering with transverse holes 49 provided in the slats, a locking bar 50 being passed through said holes 48 and 49, as shown at the right of Fig. 9, to secure the slats and end frame in assembled relation thereby enabling the operator to handle all of the slats as a unit by grasping the handle members 51 carried by the end frame bars 44.

The slats 34 are rabbeted as indicated at 53 to accommodate the rails 13 and 14 which support and guide the slats when the holder 26 is moved with the table section 7 and 8, as hereinafter described.

The use of the apparatus described herein may be explained as follows:

The grooved surface of fiber holder 26 is first completely covered by a mass of tangled fibers, such as that indicated at 31, so that portions of said mass extend across and cover the grooves 27 and 28. The slats 34, having the end frames 43 assembled therewith as previously described, are then fitted on the pins 32 so that the slats lie between and parallel with the grooves 27 and with the rabbeted surfaces of the slats facing upwardly. This assembly is initially arranged on table 20 with the supporting casters 41 resting on the upper surface of the table and with the slats 34 lying parallel with the cutters 6. The holder 26 is then moved to the left so that the grooved rollers 37 leave the table 20 and ride up on the transfer rails 21, which cooperate with said rollers to maintain the slats 34 and the grooves 27 in proper relation to the cutters 6. After the grooved rollers 37 have traveled a suitable distance along the transfer rails 21 the holder 26 and the associated slats are arranged in a vertical position by swinging them in an anti-clockwise direction about the pivotal supports afforded by the rollers 37 and their supporting shafts 38. The fiber holder and slats, after being arranged in said vertical position as indicated by dotted lines in Fig. 1, are moved against the right hand end of table section 8 and are then disposed in a horizontal position on said table section 8 by further turning movement thereof in an anti-clockwise direction about the aforesaid pivotal supports. It will thus be seen that the fiber holder 26 and the slats 34 are arranged on table section 8 in an inverted position as compared with the position which they occupy on the table 20. The fiber holder 26 and associated slats 34 are then pushed to the left a short distance along the table section 8, being maintained in proper relation to the cutters 6 by the guiding action of the guide rails 14 which fit between and support the rabbeted portions 53 of the slats. The fiber holder and the associated slats are not moved over the cutters 6 until after the end frames 43 have been removed to clear the ends of the spaces separating the adjacent slats. This removal of the end frames is accomplished by pulling out the end frame locking rods 50 and then disengaging and removing the end frames from the engaging ends of the slats. After this removal of the end frames the fiber holder and the slats are moved to the left over the revolving cutters 6 and onto the table section 7, whose guide rails 13 are also accommodated between the spaced rabbeted portions 53 of the slats. After the fiber holder and the slats have been moved beyond the cutters 6 the end frames 43 are reassembled with the slats so that the latter may be held in place during the transfer of the fiber holder from the table section 7 to the table 23. This last mentioned transfer of the fiber holder

is accomplished by moving it to the left until the grooved rollers 37 leave the table 1 and ride up upon the transfer rails 24. During travelling movement of the grooved rollers 37 along the transfer rails 24 the fiber holder and the associated slats are turned in an anti-clockwise direction through an angle of approximately 180° so that the fiber holder may be deposited on table 23 with the caster carrying surface of the holder facing downwardly, the slats 34 being thus disposed above the holder so that they can be conveniently removed and then re-assembled with the holder in preparation for a second cutting operation in which the cutters 6 traverse the grooves 28. In preparing for this second cutting operation the slats, with the end frames 43 assembled therewith, are removed from the holder and then re-assembled therewith so that the slats now lie between and parallel with the grooves 28. The resulting assembly is then arranged in a starting position on table 20 with the slats 34 facing upwardly and lying parallel with the cutters 6. The fiber holder and the slats are then moved, by the same procedure as previously described, from their starting position on table 23 to their finishing position on table 20 and, during the course of this movement, the grooves 28 are traversed by the cutters 6.

During the initial cutting operation described herein, the cutters 6 traverse the grooves 27 and cut through the portion of the fibrous mass extending across these grooves along lines paralleling said grooves. During the second cutting operation, the cutters 6 traverse the grooves 28 and cut through overhanging portions of the fibrous mass along lines at right angles to the first cuts, thereby dividing the mass of fibers into smaller masses of substantially rectangular outline, the fibers contained in such smaller masses being relatively short and easily separated from the component short fibers entangled therewith. Small sloping projections 60 are preferably arranged on the rails 13 so as to clear the spaces between the slats 34 of fibers which have been forced into these spaces during the cutting operation. It is important that these spaces be cleared after the cutting operation in order to facilitate the passage of the end frame locking rods 59 through the transverse holes 49 of the slats after the cutting operation is completed but before the fiber holder and the associated slats have been transferred from the table section 1 to the table 23.

After completion of the first cutting operation described herein, the second cutting operation may be accomplished by reassembling the holder and the fiber retaining slats on the table 23 with the slats lying between and parallel with the groove 28, then inverting this assembly, and then moving it over the cutters 6 from a starting position on table 23 to a finishing position on table 20. In this case the direction of rotation of the cutters will be reversed for the second cutting operation through the agency of a reversing switch on the motor 11a or in any other suitable manner.

Having thus described what I now consider to be the preferred embodiment of this invention it will be understood that various modifications may be resorted to within the scope and spirit of the invention as defined by the appended claims.

I claim:

1. Fiber cutting apparatus comprising a series of cutters, a fiber holder assembly comprising a base member provided with a row of parallel

grooves extending across one surface thereof, a series of separate slats for holding a mass of fibers against the grooved surface of said base member so that portions of the mass extend across said grooves, said slats being assembled with the base member so that they lie between and parallel with said grooves and end frames detachably secured to opposite ends of said slats to enable them to be handled as a unit, said cutters and said fiber holder assembly being movable relatively to each other in fiber cutting association so that the cutters are received between the slats and travel across the entire length of the slats and grooves in such manner as to cut through those portions of the fibrous mass which extend across the grooves.

2. Fiber cutting apparatus as set forth in claim 1 in which each end frame includes slat-spacing projections for insertion in sockets provided in the ends of the slats with which the end frame is associated.

3. Fiber cutting apparatus as set forth in claim 1 in which each end frame is provided with slat-spacing projections fitted in sockets provided in the adjacent ends of the slats and is also provided with parallel end portions extending a short distance along the outer sides of the outermost slats of the series and a locking pin extending transversely through holes provided in the parallel end portions of each frame and through registering transversely extending holes provided in said slats.

4. Fiber cutting apparatus as set forth in claim 1, in which the base member is provided with retaining pins extending through the mass of fibers and in which the slats are provided with openings in which the pins are fitted to hold the slats in position.

5. Fiber cutting apparatus comprising a series of rotary cutters mounted on a stationary shaft, a fiber holder having one surface thereof interrupted by two rows of intersecting grooves, the component grooves of each row being parallel with each other and open at their opposite ends and extending entirely across said surface at right angles to the grooves of the companion row, means for retaining a mass of fibers against the grooved surface of the holder so that portions of said mass extend across said grooves, said means comprising a plurality of slats adapted to be selectively assembled with the holder so that said slats lie between and parallel with the grooves of a selected one of said rows, supporting means over which the fiber holder is movable relatively to the cutters in fiber cutting association therewith so that the cutters are received between the slats and traverse the lengths of the grooves lying parallel with said slats, said cutters serving to cut through the portions of the fibrous mass extending across the grooves traversed thereby, said apparatus being characterized in that said fiber holder may move over its supporting means with the grooves of either row positioned to receive the cutters therein, the slats being assembled with the fiber holder prior to each cutting operation so as to lie parallel with the grooves positioned to receive the cutters therein.

6. Fiber cutting apparatus as set forth in claim 5 in which the fiber holder and the slats are provided with interengaging means for holding the slats in properly spaced relation and preventing displacement of the slats during the cutting operation.

7. Fiber cutting apparatus comprising a rotary shaft mounted in stationary bearings, a plurality

of laterally spaced circular cutters fixed to rotate with said shaft, table sections arranged at opposite sides of said shaft, a fiber holder provided with two rows of intersecting grooves extending across one surface thereof, the component grooves of each row being parallel with each other and open at their opposite ends and extending entirely across said surface at right angles to the grooves of the companion row and means for retaining a mass of fibres against the grooved surface of the holder so that said mass extends across said grooves, said means comprising a plurality of slats adapted to be selectively assembled with the holder so that said slats lie between and parallel with the grooves of a selected one of said rows, said holder being adapted to be initially arranged on one of said table sections with the grooves thereof facing downwardly so that the grooves of one row between which the slats are arranged are aligned with said cutters and being then movable across the cutters to the table section at the opposite side of said shaft so that, during said movement, the cutters traverse the length of the grooves aligned therewith and cut through the portions of the fibrous mass extending across said aligned grooves, said apparatus being designed to permit the aforesaid cutting operation to be repeated with the holder re-arranged so that, when the holder is again passed across the cutters from one table to the other during the second cutting operation, the cutters traverse the remaining grooves of the holder and cut through the portions of the fibrous mass extending across said remaining grooves, said slats being re-assembled with the holder prior to the second cutting oper- 35

ation so that, during said second cutting operation, they lie between and parallel with the grooves traversed by said cutters.

8. A fiber holder of the character described comprising a member provided with a row of parallel cutter-receiving grooves extending across one surface thereof, pins projecting upwardly from marginal portions of said member and means for holding a mass of fibers against the grooved surface of said member so that portions of the mass extend across the grooves, said means comprising a plurality of slats adapted to be assembled with the member so that the slats lie between and parallel with said grooves, said slats being provided with openings in which said pins are fitted to hold the slats against longitudinal or lateral displacement relative to said member.

9. A fiber holder of the character described comprising a member having two intersecting rows of grooves in one surface thereof, the grooves of each row being open at both ends and extending entirely across said surface at right angles to the grooves of the remaining row and means for retaining a mass of tangled fibers against the grooved surface of said member so that portions of the mass extend across all of said grooves, said means comprising a plurality of slats adapted to be selectively assembled with said member so as to lie between and parallel with the grooves of either row and pins projecting from the grooved surface of said member and adapted to be fitted in openings provided in said slats to hold the slats against longitudinal or lateral displacement relative to said member.

JAN V. WEINBERGER.
